UNITED STATES PATENT OFFICE

2,480,622

ELECTRIC SWITCH

Frank E. Warnock, Merwood, Pa., assignor to
 General Electric Company, a corporation of
 New York

Application December 4, 1945, Serial No. 632,734

3 Claims. (Cl. 200—146)

1

My invention relates to electric circuit disconnecting switches, and more particularly to those of the load break switch type wherein auxiliary arcing contacts are provided to interrupt currents such as transformer magnetizing currents and the like, in addition to the main switch members for carrying the normal load current and disconnecting the circuit.

Such load break disconnecting switches, in a relatively inexpensive yet fully insulated and readily mounted and interconnected form, can be used with advantage for both interrupting and disconnecting a high voltage power circuit at points where conventional power circuit breakers are impractical or uneconomical. Also it is desirable that electric switches for interrupting the magnetizing current of power transformers be of a form adapted to be immersed in a relatively small space in the same liquid insulating dielectric such as oil or a halogenated hydrocarbon as the transformer. Thus when arcs are drawn in oil there is always the hazard of fire. On the other hand, when arcs are drawn in a non-inflammable dielectric, there is always the possibility of some decomposition of the halogenated hydrocarbons and the consequent formation of corrosive decomposition products that are injurious to transformer insulation as well as other parts.

Accordingly it is an object of my invention to provide a new and improved form of load break switch that is capable of efficiently interrupting moderate load currents of high voltage power circuits within a relatively small hermetically-sealed and evacuated enclosure in addition to externally carrying the load currents and disconnecting the power circuits.

It is another object of my invention to provide a switch of the type described above which may be immersed in any form of liquid insulating dielectric without fire hazard or deleterious effect on the liquid dielectric when operating to interrupt moderate load currents.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is an elevational view, partly in section, of an electric switch embodying my invention with the switch shown in the closed position, and Fig. 2 is a view similar to Fig. 1

2

showing the switch during the circuit opening operation.

The load break disconnect switch illustrated in the drawing comprises a pair of stationary high voltage power circuit terminals, 1 and 2, which may be referred to as first and second circuit terminals, respectively. These circuit terminals are illustrated as being supported on the spaced-apart integrally mounted high voltage insulated supports 3 and 4, respectively. Although the electric switch shown in the drawing is illustrated as being mounted in air, it should be understood that it is particularly well adapted for being immersed in a liquid insulating dielectric, in which case it may be mounted in a relatively small housing integral with a transformer, as is disclosed for example, in copending Palme and McCarty application Serial No. 632,735, now Patent No. 2,469,203, May 3, 1949, filed concurrently with the present application, and assigned to the same assignee as the present application.

Circuit terminals 1 and 2 are arranged to be electrically interconnected by a pair of relatively movable knife switch members illustrated as a stationary switch member or contact 5, electrically connected and supported from circuit terminal 1, and a movable blade or contact 6 pivotally mounted as indicated at 7 to circuit terminal 2 and having load current-carrying overlapping engagement with the switch member 5 when the pivotally mounted rotatable blade 6 is in a predetermined angular position as shown in Fig. 1.

For the purpose of interrupting moderate load power currents when the electric switch of my invention is to be opened, there is provided a relatively small auxiliary circuit interrupter, generally indicated at 8, which can be carried directly by one of the relatively movable switch members without requiring any additional insulating support. As illustrated, circuit interrupter 8 is associated with stationary contact or switch member 5, and circuit terminal 1 by means of Z-shaped conducting supporting member 9. It should be understood that circuit interrupter 8 might be carried by movable blade 6 if desired. Circuit interrupter 8 comprises an hermetically sealed enclosure 10 formed of insulating material such as glass, or the like, which is essentially an evacuated envelope for housing a pair of relatively movable arcing or interrupting contacts 11 and 12. Interrupting contact 11 is illustrated as a stationary contact electrically connected to stationary current carrying contact 5 by means of Z-shaped bracket or support 9. Movable arcing contact 12, on the other hand,

is a rod-shaped contact having a portion thereof extending outside of evacuated envelope 10 through a flexible member or diaphragm 13. The portion of rod contact 12 extending outside of housing 10 is in effect a contact actuating member and includes at the outer extremity thereof an auxiliary terminal 14 which is positioned outside of housing or enclosure 10. Relatively movable arcing or interrupting contacts 11 and 12 are preferably biased to the open position by suitable means such as the flexible diaphragm 13 or if desired, by additional spring means such as 15.

Supported on movable blade 6 is an auxiliary contact surface in the form of a conducting lever or transfer switch 16. Lever 16 is pivotally mounted as indicated at 17 and is normally biased in a counter-clockwise direction, as viewed in Fig. 1, by resilient means, such as a spring 18, such counter-clockwise movement being limited by a stop 19 on blade 6 adapted to engage with an extension 20 of lever 16.

The auxiliary contact surface in the form of lever 16, the auxiliary terminal 14, together with interrupting contacts 11 and 12, provide a shunt electrical connection across the relatively movable switch members 5 and 6. An important feature of my invention is the arrangement of the current carrying contacts and arcing contacts whereby the current carrying contacts are first opened thereby shunting all of the power current through circuit interrupter 8. As illustrated in the drawings, a portion of the current is normally shunted through the circuit interrupter 8 but it will be understood that the circuit through interrupting contacts 11 and 12 may normally be open until just prior to disengagement of the current carrying contacts. Such an arrangement is disclosed and claimed in the above-mentioned copending application of Palme and McCarty.

As illustrated by dotted lines in Fig. 2, arcing contacts 11 and 12 remain in current carrying engagement until after current carrying contacts 5 and 6 have been disengaged and all of the current has been transferred to the shunt circuit comprising interrupting or arcing contacts 11 and 12. Furthermore, contacts 5 and 6 must have separated a sufficient distance before contacts 10 and 11 separate so that arcing will not occur at contacts 5 and 6. Spring 18, which is a stronger spring than spring 15, maintains arcing contacts 11 and 12 in a closed position during the opening movement of blade 6 and until extension 20 of lever 16 engages stop 19. Thereafter, arcing contacts 11 and 12 are separated under the influence of spring 15 and in view of the high vacuum in envelope 10 the interrupting operation even with very high voltages is readily accomplished. It will be observed that the auxiliary contact surface in the form of lever 16 is separated from auxiliary terminal 14 thereby providing an additional insulating gap in the shunt circuit including interrupting contacts 11 and 12. The other gap is provided by contacts 11 and 12 which, during the opening operation of the switch, are opened and remain open.

During the circuit closing operation the circuit is first completed through the shunt circuit including arcing contacts 11 and 12 after which the main current carrying contacts 5 and 6 are closed to complete the circuit.

It will be understood that the insulating evacuated envelope 10 prevents any arc which is drawn from, in any way, deleteriously affecting the sur-

rounding medium whether it be air or oil or other liquid insulating dielectric.

It should be understood that my invention is not limited to the specific details of construction and arrangement thereof herein illustrated and that changes and modifications may occur to one skilled in the art without departing from the spirit of my invention.

What I claim as new and desire to secure by Letters Patent of the United States is:

1. In a load break disconnecting switch, a first insulating support for a first circuit terminal, a second insulating support for a second circuit terminal, a pair of relatively movable cooperating switch members which when brought into electrical engagement complete a circuit between said circuit terminals, one of said switch members comprising a movable blade, a circuit interrupter carried by said first insulating support and comprising a first interrupting contact electrically connected to said first circuit terminal, a cooperating movable interrupting contact, an evacuated envelope for housing said interrupting contacts comprising flexible means through the movement of which said movable contact engages or disengages said first interrupting contact, an auxiliary terminal external to said envelope electrically connected to said movable interrupting contact, an auxiliary contact surface carried by said blade, means including said auxiliary contact surface, said auxiliary terminal and said interrupting contacts for providing a shunt electrical connection between said switch members before the members are moved out of electrical engagement, a spring mounted on said blade to maintain said shunt connection during a portion of the opening movement of said switch members, a stop for limiting the effective operation of said spring, spring means for separating said interrupting contacts to draw an arc and extinguish the same within said envelope upon continued opening movement of said switch members and to provide a gap in said shunt circuit, and means including said stop for subsequently providing an additional insulating gap in said shunt circuit between said auxiliary terminal and said auxiliary contact surface.

2. In a load break disconnecting switch, a pair of switch members integrally mounted for load current carrying, overlapping engagement and including a pivotally mounted rotatable blade, a relatively small current interrupter having a hermetically sealed and evacuated enclosure fixedly mounted on one of the switch members and provided with a first interrupting contact fixedly extending through the enclosure and electrically connected to the one switch member, and a second interrupting contact extending through and having a flexible seal with the enclosure through the movement of which the second interrupting contact engages or disengages the first interrupting contact, an auxiliary movable terminal external to the enclosure mechanically connected to operate the second interrupting contact and electrically connected therewith, an auxiliary contact surface carried by and electrically connected to the other switch member for engaging the external terminal to interconnect the interrupter contacts in shunt with the pair of switch members during current-carrying engagement thereof, resilient biasing means for maintaining engagement between the auxiliary contact surface and the auxiliary terminal upon disengagement of the switch members, and means including the auxiliary terminal and the auxiliary contact sur-

face for disengaging the interrupting contacts to draw an arc and extinguish the same within the enclosure upon further opening of the switch members.

3. In a load break disconnecting switch, a pair of knife switch members having load current carrying overlapping engagement and each having a spaced apart insulating support, a relatively small current interrupter having an evacuated envelope supported on one of the switch members substantially in the space between the insulating supports when the switch members are in engagement and provided with a first interrupting contact extending through the envelope and electrically connected to the one switch member, and a second interrupting contact extending through and having a flexible seal with the envelope through the movement of which the movable interrupting contact engages or disengages the first interrupting contact, an auxiliary movable terminal external to the envelope mechanically connected to operate the second interrupting contact and electrically connected therewith, an auxiliary contact surface extending from and electrically connected to the other of said switch members for engaging said movable auxiliary terminal to interconnect the interrupter contacts in shunt with the switch members during current-carrying engagement thereof, resilient means for maintaining engagement between the auxiliary contact surface and the auxiliary terminal to maintain the

shunt electrical circuit including the interrupting contacts between the current-carrying switch members after the disengagement thereof, means including the auxiliary terminal and the auxiliary contact surface for separating the interrupting contacts to draw an arc in the shunt circuit and extinguish the same within the envelope after the disengagement of the switch members, and means including the auxiliary terminal and the auxiliary contact surface for providing an insulating gap in the shunt circuit upon continued opening of the switch members after the disengagement of the interrupting contacts.
